UNITED STATES PATENT OFFICE.

NANCY VICTORINE ARMSTRONG, OF TORONTO, ONTARIO, CANADA.

DESIGN FOR AN OUTER GARMENT.

56,331.

Specification for Design.

Patented Oct. 5, 1920.

Application filed March 25, 1920. Serial No. 368,760. Term of patent 14 years.

To all whom it may concern:

Be it known that I, NANCY VICTORINE ARMSTRONG, a citizen of the United States, residing in the city of Toronto, in the county of York, in the Province of Ontario, Canada, have invented a new, original, and ornamental Design for an Outer Garment, of which the following is a specification, reference being had to the accompanying drawing, forming part thereof.

Figure 1 is a front view of a garment.

Fig. 2 is a back view thereof, showing the same provided with a drop seat which is adapted to be turned up and detachably secured to the back of the waist of a garment, said drop seat having a belt extending around the body.

Fig. 3 is a similar view to Fig. 2 showing the drop seat in the turned up or closed position.

The design consists of an outer garment provided with a drop seat and belt as shown.

I claim:

The ornamental design for an outer garment as shown.

NANCY VICTORINE ARMSTRONG.
